UNITED STATES PATENT OFFICE.

GEORGE ARTHUR CONLAN, OF TORONTO, ONTARIO, CANADA, ASSIGNOR OF ONE-HALF
TO ALAN C. THOMPSON, OF TORONTO, ONTARIO, CANADA.

MATTRESS AND THE LIKE.

1,393,755.

Specification of Letters Patent. Patented Oct. 18, 1921.

Application filed December 8, 1920. Serial No. 429,125.

To all whom it may concern:

Be it known that I, GEORGE ARTHUR CONLAN, of the city of Toronto, in the county of York, Province of Ontario, Canada, have 5 invented certain new and useful Improvements in Mattresses and the like, of which the following is a specification.

This invention relates particularly to mattresses formed of felt or similar material, 10 which has a tendency when in use to become more or less compacted and flattened. Such mattresses sooner or later become more or less flattened out and the result is that the ticking at the edges bulges outwardly spoiling 15 the appearance of the mattress. The shape of the sides of the mattress is further spoiled owing to the common practice of sitting on the edge of the bed.

In the present invention, my object is to 20 provide a mattress which will not be materially more expensive than an ordinary felt mattress and in which the edges will remain in shape even after long periods of use.

I attain my object by means of the constructions hereinafter described and illustrated in the accompanying drawings in 25 which—

Figure 1 is a cross section of a portion of 30 a mattress constructed in accordance with my invention; and

Fig. 2 a horizontal section of part of the same.

In the drawings like numerals of reference indicate corresponding parts in the different figures.

The body of the mattress is formed of 35 fibrous filling 1. This preferably comprises a plurality of layers of felt such as commonly employed in mattress construction.

40 This fibrous filling usually extends out to each edge of the mattress. In my mattress, however, I position around the sides of the mattress an edging of coil springs 2

having their axes normal to the top and bottom surfaces of the mattress. These 45 coil springs may be secured in position in any desired manner. I prefer, however, to locate the springs in a series of connected pockets 3 of textile fabric, these pockets being usually formed by transversely stitching 50 a long strip of folded cotton fabric. Around the spring edging is preferably wrapped a piece of felt fabric 4, as seen particularly in Fig. 1. The mattress is inclosed in the usual ticking 5 and the parts of the mattress are 55 secured together in the ordinary way by suitable tufting 6.

The result of this construction is that the spring edging always tends to extend itself to the limit and thus always keeps the sides 60 of the ticking properly stretched, thus maintaining substantially rectangular shape in section of the edges of the mattress.

As the greater part of the filling of the mattress is of felt or similar material, the 65 mattress is not nearly so expensive as one formed completely of coil springs, while the mattress retains its shape and appearance substantially as well as such a spring mattress.

70

What I claim as my invention is:—

1. A mattress comprising a fibrous filling; an edging of coil springs having their axes normal to the top and bottom surfaces of the mattress; a ticking; and tufting securing 75 the parts of the mattress together.

2. A mattress comprising a fibrous filling; an edging of coil springs secured in a series of connected pockets of textile fabric, the springs having their axes normal to the top 80 and bottom surfaces of the mattress; a ticking; and tufting securing the parts of the mattress together.

Signed at Toronto this 6th day of October, 1920.

GEORGE ARTHUR CONLAN.
